UNITED STATES PATENT OFFICE.

EPPA H. RYON, OF PASADENA, CALIFORNIA, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

Application filed October 20, 1923. Serial No. 669,870.

To all whom it may concern:

Be it known that I, EPPA H. RYON, a citizen of the United States, residing at Pasadena, in the county of Los Angeles and State 5 of California, have invented a new and useful Weft-Detecting Mechanism, of which the following is a specification.

This invention relates to weft detecting mechanism for a weft replenishing loom and 10 particularly to certain improvements in the type of weft detecting mechanism shown in my prior Patents No. 1,345,508, No. 1,369,- 473 and No. 1,372,316. In this type of mechanism, the transferrer is given a transfer- 15 ring movement at regularly repeated intervals, commonly on each alternate beat of the lay, and the detecting devices are mounted to move with the transferrer. The weft-engag- 20 ing member is preferably of the "slip- feeler" type and swings upon its pivot when there is too little yarn on the bobbin to prevent movement of the weft-engaging member along the bobbin or weft carrier. An indicating device on the transferrer is moved 25 to operative position when such slipping or angular movement of the detecting member occurs and it is one object of my invention to provide means effective to complete such movement of the indicating device to operative 30 position after an initial movement has been given thereto by the weft-engaging detecting member.

When the indicating device is in operative position it acts to indicate substantial weft exhaustion and to release a corresponding weft carrier as in my prior patents.

A second object of my invention is to provide an improved actuating device for engaging the detecting mechanism and advancing the detecting member as the trans- 40 ferrer moves downward.

A third feature of my invention relates to certain improvements in the construction of the resetting device.

45 My invention further relates to arrangements and combinations of parts which will be hereinafter described and more particularly pointed out in the appended claims.

A preferred form of the invention is 50 shown in the drawings in which—

Fig. 1 is a left hand side elevation of parts of a stationary weft carrier magazine embodying my improvements;

Fig. 2 is a sectional front elevation, taken 55 along the line 2—2 in Fig. 1;

Fig. 3 is an enlarged detail perspective view, looking in the direction of the arrow 3 in Fig. 2;

Fig. 4 is an enlarged rear elevation of the transferrer and the detecting mechanism 60 mounted thereon, with certain parts shown in section; and

Figs. 5 and 6 are views similar to Fig. 4 but showing the parts in different successive positions.

Referring to the drawings, I have shown a portion of a stationary magazine of the general type more fully disclosed in my prior Patent No. 1,372,316 and comprising 70 a frame 10 upon which are mounted vertically sliding bars 11 movable by arms (not shown) projecting from a casting 12 which is supported for angular and longitudinal movement by a rod or shaft 13. The sliding bars 11 are connected to actuate delivery devices or cradles in the magazine by which a selected weft carrier may be released and advanced to transfer position upon indication of weft exhaustion of a particular kind 75 or color of weft.

The parts thus far described are of the usual type and in themselves comprise no part of my present invention.

A transferrer 15 is pivoted at 16 on the magazine frame 10 and is actuated through a link 17 by a cam (not shown) or other suitable actuating mechanism, said mechanism giving the transferrer 15 a downward transferring movement at regular intervals, 80 preferably at every alternate beat of the lay, as fully shown and described in my prior patent No. 1,372,316.

The transferrer 15 is provided with an offset member 20 which is of open section 85 and supports a lever 21, to one end of which is pivotally secured at 22 a weft engaging or detecting member 23. An adjustable stop screw 24 engages a shoulder 25 on the lever 21 and limits swinging movement of the detecting member 23 in one direction.

A link 26 is pivoted at 27 to the member 23 and at its opposite end has a swivel connection with a piston or slide 28 mounted in a bearing 29 in the offset portion 20 of the transferrer 15. A spring 30 is interposed between the head of the link 26 and the end of the bearing 29 and yieldingly moves the member 23 and lever 21 to the normal or raised position shown in Fig. 4.

A stud or pin 31 (Fig. 4) is slidably 110

mounted in the bearing 29 and is preferably provided with a V-shaped groove 32 and a conical end 33. A block 34 is slidably mounted in a transverse recess in the trans-
5 ferrer head 20 and is yieldingly forced against the pin 31 by a flat spring 35. The head or weft-engaging part 36 of the detecting member 23 is preferably ribbed or toothed as shown in Figs. 4 to 6 and is
10 held from slipping axially of the bobbin by engagement of these ribs or teeth with the weft on the weft carrier. The parts thus assume the relative position shown in Fig. 5 during downward movement of the trans-
15 ferrer when the detecting member engages a full or partially full bobbin.

If, however, the weft on the bobbin is substantially exhausted, the teeth on the detector head will secure no grip upon the
20 bobbin and the offset application of pressure to the detecting member will cause said member to rock as indicated in Fig. 6. Such movement compresses the spring 30 and advances the piston or slide 28 to advance
25 the pin 31 to project beyond the face of the transerrer.

Engagement of the detecting member 23 with the weft carrier or bobbin is caused by contact of a lug 40 (Fig. 1) on the free end
30 of the lever 21 with the head 41 of a lever 42 mounted upon a fixed pivot 43 and held yieldingly in adjusted raised position by a
35 spring 44. If rocking movement of the lever 21 is restricted by engagement of the member 23 with a full weft carrier, as indicated in Fig. 5, the head 41 and arm 42 are
40 swung downward against the yielding tension of the spring 44.

The sliding block 34 normally holds the
40 pin 31 from accidental displacement and also has the further function that it assists in advancing the pin 31 to the indicating position shown in Fig. 6 by engagement of the block with the conical end surface 33
45 after the block is forced out of the V-shaped groove 32. The slide 28 thus produces an initial movement only of the pin 31 and further movement thereof is caused or assisted by the block 34.

50 As the transerrer 15 rises with the pin 31 in the position shown in Fig. 6, the pin engages the bevel or cam face 46 of an actuating lever 47 (Figs. 1 and 3) pivoted at 48 on the magazine frame 10 and connected to rock the casting 12 and selectively raise one
55 of the slides 11. As the transerrer 15 approaches its upper limit of travel, it engages a yielding stud or stop 49 mounted on the bell crank lever 47 and rocks the lever 47 and lever 12 in the opposite direction. If there has been no change in the longitudinal position of the casting 12, the indicated weft carrier will be released and will descend to transfer position.

60 65 The bell crank 47 is provided with a cam

surface 50 spaced above the cam surface 46 and effective to force the pin or stud 31 back to the normal position shown in Fig. 4 when this surface is engaged by the pin 31 during the continued upward movement of the transerrer 15. It sometimes happens that the transerrer is not raised to its extreme upper limit of movement, particularly if the loom is being turned by hand, and accordingly I provide a third cam surface 51 on the bell crank 47 so that the pin 31 may be reset by downward movement if it is not raised sufficiently to be reset by the cam surface 50 upon continued upward movement. Provision is thus made for resetting the pin 31 under any and all conditions of operation.

Having thus described my invention and the advantages thereof, it is believed that the operation will be readily apparent to those skilled in the art. It will be also evident that changes and modifications can be made therein within the spirit and scope of the claims hereto appended. Accordingly I do not wish to be otherwise limited to the details herein disclosed but what I claim is:

1. In a weft replenishing loom, in combination, a transerrer, a detecting member mounted on said transerrer and movable therewith, an indicating device receiving initial indicating movement from said detecting member, and separate means to complete said indicating movement.

2. In a weft replenishing loom, in combination, a transerrer, a detecting member mounted on said transerrer and movable therewith, an indicating device receiving initial indicating movement from said detecting member, and a spring actuated device effective to complete said indicating movement.

3. In a weft replenishing loom, in combination, a transerrer, a detecting member mounted on said transerrer and movable therewith, an indicating device receiving initial indicating movement from said detecting member, said device having a surface thereon inclined with respect to its direction of movement, and yielding means positioned to engage said inclined surface and complete said indicating movement.

4. In a weft replenishing loom, in combination, a transerrer, a detecting member mounted on said transerrer and movable therewith, an indicating device receiving initial indicating movement from said detecting member, a link effective to transmit movement from said detecting member to said indicating device but having no positive connection with said device, and a spring yieldingly resisting movement of said member and link from normal position.

5. In a weft replenishing loom, in combination, a transerrer, a detecting member

mounted on said transerrer and movable therewith, an indicating device receiving initial indicating movement from said detecting member, and a lever having a cam surface engaged by said indicating device in its upward movement for actuation thereby, said lever having a second cam surface effective to reset said indicating device upon continued upward movement thereof, and having also a third cam surface effective to reset said indicating device upon subsequent downward movement thereof.

6. In a weft replenishing loom, in combination, a transerrer, a detecting member mounted on said transerrer and movable therewith, an indicating device receiving initial indicating movement from said detecting member, and a lever engaged by said indicating device in its upward movement for actuation thereby, said lever having a yielding stop mounted thereon and

engaged by the transerrer upon its upward movement for yielding actuation thereby in the opposite direction.

7. In a weft replenishing loom, in combination, a weft carrier magazine having a frame, a transerrer having a main arm and a laterally projecting end portion, a lever of substantially the length of said end portion and positioned above said portion with its ends adjacent the ends of said portion, said lever and end portion being pivotally connected near their middle points, a detecting member pivoted to one end of said lever adjacent the outer projected end of said transerrer, and a device yieldingly engaging the opposite end of said lever adjacent the main arm of said transerrer, to give said member a detecting movement.

In testimony whereof I have hereunto affixed my signature.

EPPA H. RYON.
